(57) **CLAIM**

The ornamental design for a canoe support, as shown and described.

DESCRIPTION

FIG. 1 is a perspective view of a canoe support; FIG. 2 is a front view of the canoe support of FIG. 1; FIG. 3 is a right side view of the canoe support of FIG. 1; FIG. 4 is a back view of the canoe support of FIG. 1; FIG. 5 is a top view of the canoe support of FIG. 1; and, FIG. 6 is a bottom view of the canoe support of FIG. 1. The broken lines shown in the drawings are included for the purpose of illustrating environmental structure and form no part of the claimed design.
